SHAVING BRUSH AND RAZOR HOLDER

Charles T. Oppermann, Jr., Detroit, Mich.

Application April 20, 1948, Serial No. 145,827

Term of patent 3½ years

(Cl. D4—3)

To all whom it may concern:

Be it known that I, Charles T. Oppermann, Jr., a citizen of the United States, residing at Detroit, in the county of Wayne and State of Michigan, have invented a new, original, and ornamental Design for a Shaving Brush and Razor Holder, of which the following is a specification, reference being had to the accompanying drawings, forming a part thereof, in which:

Fig. 1 is a front elevational view of a shaving brush and razor holder embodying the invention; and

Fig. 2 is a side elevational view of the right side of the shaving brush and razor holder as viewed in Fig. 1; and

Fig. 3 is a top plan view; and

Fig. 4 is a side elevational view of the left side of the shaving brush and razor holder as viewed in Fig. 1; and

Fig. 5 is a view in perspective.

I claim:

The ornamental design of a shaving brush and razor holder, substantially as shown.

CHARLES T. OPPERMANN, JR.
